UNITED STATES PATENT OFFICE.

JACUB SCHWARTZMAN, OF BROOKLYN, NEW YORK.

WIRE FABRIC.

1,116,500.

Specification of Letters Patent. Patented Nov. 10, 1914.

Application filed July 18, 1913. Serial No. 779,677.

To all whom it may concern:

Be it known that I, JACUB SCHWARTZMAN, a citizen of the United States, residing at Brooklyn, in the county of Kings and State of New York, have invented certain new and useful Improvements in Wire Fabrics, of which the following is a specification.

This invention relates to wire or metallic fabrics, the object of the invention being to provide an improved fabric of this character particularly adapted for use in connection with spring mattresses, and which will be simple in construction, durable in use, and comparatively inexpensive to manufacture, the said fabric embodying an improved form of edge link whereby the edge of the fabric may be properly reinforced so that when the fabric is assembled the pull on the several links will be in a straight direction lengthwise of the fabric while such fabric will be unusually resilient owing to the peculiar construction of the links.

A further object of the invention is the provision of an improved fabric forming side link.

In the drawings accompanying and forming part of this specification, Figure 1 is a plan view of this improved fabric showing the edge reinforced with the edge forming link and also with a resilient strip, either of which forms of reinforcement may be used independently or they may both be used together; Fig. 2 is a detail view, full size, of one of the improved links for the body of the fabric; Fig. 3 is an edge view of the link shown in Fig. 2; Fig. 4 is a view, full size, of one of the improved edge forming links; Fig. 5 is an edge view of the link shown in Fig. 4; and Fig. 6 is a detail view illustrating another way of assembling the same form of links.

Similar characters of reference indicate corresponding parts throughout the several figures of the drawings.

In the form shown the fabric is made up of a series of interconnected or interlocked units 2 each comprising a pair of relatively straight portions 3 and 4 running in substantial parallelism with each other and connected at their ends by a cross-forming portion 5, thus forming a link somewhat resembling a capital letter U. The straight portions 3 and 4 of the link terminate in hooks or loops 3' and 4' respectively at one end of

the link and at the opposite end of the link each merges into an angular formed portion 6 made up of a pair of inclined portions 7 and 8 which at their juncture points are offset one from the other as at 9, the inclined portion 8 in turn being bent inwardly as at 10 to form an eye or loop 11 resembling somewhat the shape of an inverted V, such loop or eye terminating in the cross member 5. Each angular formed portion extends outwardly so that the link at this point is of greater width than at any other point thereof, while the cross member 5 is located inwardly of the extreme end of the link. These angular portions of the link are for the purpose of permitting an efficient and effective interlocking or interconnecting of one link with a companion link in the manner shown in Fig. 1, in which it will be observed that the companion links are as it were twisted together, this being permitted by reason of the offset portions 9 of each link which offset portions constitute the connecting part between the inclined portions forming the triangular portion of the link at this point.

For reinforcing and strengthening the edge, the side link shown in Fig. 4 may be used. The side link is of the form shown in Figs. 4 and 5 and has a triangular portion similar to that hereinbefore described in the U-shaped link. This improved side or edge link comprises a pair of parallel straight portions located relatively close together and each terminating in a hook or loop, one of such straight portions being at its opposite end integrally connected with the other straight portion by a triangular portion having an offset whereby it may be readily interwoven with the companion links forming the fabric adjacent to the apex of such triangular portion.

When the several units or links have been assembled in the manner shown they may be connected to the cross angle bar by suitable helical springs 13. In the form shown in Fig. 6 the U-shaped units or links instead of being connected or interlocked directly may be connected by means of a ring 15, which, however, is interlocked with the triangular portions of the links.

It will be observed that by means of the present improved structure the pull on the links is in a straight direction lengthwise.

thereof, and it will also be observed that considerable resiliency is obtained both lengthwise and sidewise of the fabric.

In practice one end of the fabric may be reinforced by a crosswise extending rod threaded through the links in the manner shown in Fig. 1 at 25, the ends of the rod having loops for the reception of hooks or loops of the links located at the edges of the fabric. In assembling the links they are assembled in rows in the manner shown in Fig. 1 so that the bulged or triangular formed offset portions will be interlocked or twisted together.

I claim as my invention:

1. A wire fabric for bed springs comprising a multiplicity of wire units arranged in rows, and edge links interconnected with a row of such units, each of said edge links comprising a pair of parallel straight portions located relatively close together and integrally connected by a triangular portion.

2. A wire fabric for bed springs comprising a multiplicity of wire units arranged in rows, and edge links interconnected with a row of such units, each of said edge links comprising a pair of parallel straight portions located relatively close together and integrally connected by a triangular portion, said triangular portion having an offset portion.

3. A wire fabric for bed springs comprising a multiplicity of wire units arranged in rows, and a series of edge links interconnected with a row of such units, each of such edge links comprising a pair of parallel straight portions terminating in loops or hooks at one end, one of said straight portions being shorter than the other and integrally connected with the other at the opposite end.

4. A wire fabric for bed springs comprising a multiplicity of wire units arranged in rows, and a series of edge links interconnected with a row of such units, each of such edge links comprising a pair of parallel straight portions terminating in loops or hooks at one end, one of said straight portions being shorter than the other and integrally connected with the other at the opposite end by a triangular shaped portion.

5. A wire fabric for bed springs comprising a multiplicity of wire units arranged in rows, and a series of edge links interconnected with a row of such units, each of such edge links comprising a pair of parallel straight portions terminating in loops or hooks at one end, one of said straight portions being shorter than the other and integrally connected with the other at the opposite end by a triangular shaped portion having an offset therein.

6. A wire fabric for bed springs comprising a multiplicity of wire units arranged in rows, each unit consisting of a substantially

U-shaped link having a pair of triangular portions each provided with an offset, and a row of edge links interconnected with a row of such wire units at the offset portions thereof, each edge link comprising a pair of parallel straight portions located relatively close together and terminating at one end in hooks or loops and at the other end in a triangular portion having an offset.

7. A wire fabric for bed springs comprising a multiplicity of wire units arranged in rows, each unit consisting of a substantially U-shaped link having a pair of triangular portions each provided with an offset, and a row of edge links interconnected with a row of such wire units at the offset portions thereof, each edge link comprising a pair of parallel straight portions located relatively close together and terminating at one end in hooks or loops, one of such straight portions being shorter than the other and integrally connected with the other by a laterally projecting portion having an offset.

8. A wire fabric for bed springs comprising a multiplicity of wire units arranged in rows, each unit consisting of a substantially U-shaped link having a pair of triangular portions each provided with an offset, and a row of edge links interconnected with a row of such wire units at the offset portions thereof, each edge link comprising a pair of parallel straight portions located relatively close together and terminating at one end in hooks or loops, one of said straight portions being shorter than the other and integrally connected with the other by a triangular shaped portion having an offset.

9. A side or edge link for a metallic fabric comprising a pair of parallel straight portions terminating at one end in loops or hooks and at the other end in a triangular portion.

10. A side or edge link for a metallic fabric comprising a pair of parallel straight portions terminating at one end in loops or hooks and at the other end in a triangular portion having an offset, said straight portions being located relatively close together.

11. A side or edge link for a metallic fabric comprising a pair of parallel straight portions located relatively close together and terminating at one end in loops or hooks, one of said straight portions being shorter than the other and connected with the other by a triangular portion.

12. A side or edge link for a metallic fabric comprising a pair of parallel straight portions located relatively close together and terminating at one end in loops or hooks, one of said straight portions being shorter than the other and connected with the other by a triangular portion, said triangular portion having an offset.

13. A side or edge link for a metallic fabric comprising a pair of parallel straight

portions terminating at one end in loops or hooks, one of said straight portions being shorter than the other and connected to the other by a laterally projecting portion.

5 14. A side or edge link for a metallic fabric comprising a pair of parallel straight portions terminating at one end in loops or hooks, one of said straight portions being shorter than the other and connected to the other by a laterally projecting portion of substantially triangular shape.

10 15. A side or edge link for a metallic fabric comprising a pair of parallel straight portions terminating at one end in loops or hooks, one of said straight portions being shorter than the other and connected to the other by a laterally projecting portion of

substantially triangular shape, said laterally projecting portion having an offset.

16. A metal fabric for bed springs comprising a multiplicity of wire units arranged in rows, one unit connected with another, and a series of edge links connected with a row of units and each terminating at one end in loops or hooks, and a crosswise extending rod having a loop or hook at one end for the reception of the loops or hooks of an edge link, each of such edge links comprising a pair of parallel straight portions and a triangular portion having an offset.
